UNITED STATES PATENT OFFICE.

PHILIP P. MEYER, OF NEW YORK, N. Y.

DESIGN FOR AN URN FOR HOT WATER, &c.

Specification forming part of Design No. 6,382, dated February 4, 1873.

To all whom it may concern:

Be it known that I, PHILIP P. MEYER, of the city, county, and State of New York, have invented a Design for an Urn for Hot Water and other liquids, of which the following is a specification:

The nature of my design is fully represented in the accompanying drawing, to which reference is made.

A is a stand for a lamp, and B is the urn proper, which is for holding hot water or other liquid and keeping it hot. The stand is of cylindrical form and is supported on feet *a a*. It has a flange, *b*, at its lower edge, and above this is a plain surface surmounted by three contiguous beads, *c c*, the middle of which is larger than the others. Next is a perforated portion, *d*, studded with holes or openings of ornamental form, as represented. A short distance higher up is another perforated portion, *d'*, likewise studded with ornamental perforations. Some distance above this is a bead, *f*, which terminates the stand. On opposite sides of the stand may be handles *g g*. The urn proper is at the bottom reduced in diameter to

fit within the stand, as shown by dotted lines. It has formed near the bottom a bead, *e*, which meets the bead, *f*, on the stand. Next is a plain surface surmounted by three beads, *h h*, the intermediate of which is largest. At this point there may project from the urn a spout or cock, *i*. Above the beads just alluded to the urn is contracted in dome shape to a fillet, *j*, which is surmounted by a cavetto, *k*. Two beads, *l l*, of uniform size, come next, and above them is another cavetto, *m*. This is surmounted by another fillet, *n*, above which is an ogee curve, *o*. Two beads, *p p*, interposed by a surface studded with ornamental perforations, surmount the whole. Handles *r r* may be provided on opposite sides of the urn itself. In its horizontal section the urn may be either oval or circular.

What I claim is—

A new and original design for urns, substantially as shown and described.

PH. P. MEYER.
